[57] CLAIM

The ornamental design for a combined lipstick and cigarette lighter or similar article, as shown and described.

DESCRIPTION

FIG. 1 is a perspective view of a combined lipstick and cigarette lighter showing my new design, the opposite side being a mirror image of the side shown;

FIG. 2 is an end view of the lipstick portion; and
FIG. 3 is an end view of the lighter portion.

The design is for an optionally exchangeable lipstick element to accommodate color and shade desires of the user.
